UNITED STATES PATENT OFFICE.

WILLIAM SCHONFIELD, OF LONDON, ENGLAND.

OPERATOR FOR SWINGING WINDOWS.

Application filed March 7, 1922. Serial No. 541,829.

To all whom it may concern:

Be it known that I, WILLIAM SCHONFIELD, a subject of the King of Great Britain and Ireland, residing at 8 Goring Street, St. 5 Mary Axe, London, E. C. 3., have invented new and useful Improvements in and Connected with Operators for Swinging Windows, on which application has been made for Letters Patent in Great Britain, No. 10 9658, filed 31st March, 1921, of which the following is a specification.

The present invention relates to improvements in that class of apparatus for opening and closing skylights, fanlights, 15 casement windows and the like in which a screw threaded rod pivotally mounted on the sash passes through and is actuated by a nut pivotally mounted on the fixed framing.

This class of apparatus has the disadvantage in use that the time employed in opening or closing a casement window or the like is relatively considerable as compared with an ordinary casement fastening.

The object of the present invention is to 25 provide means whereby the nut can be released at will from the screw threaded rod to allow of the window being moved to the desired position without it being necessary to screw the rod through the nut to reach that 30 position.

Briefly stated the present invention comprises the use of the class of apparatus described, of a solid mutilated nut with a threaded portion on each side of the bore in 35 parallel alignment. This mutilated nut is pivotally mounted in a bracket attached to the window frame and controlled by a spring tending to keep the internal threads on opposite sides of the bore of said nut in engagement with the screw threaded rod.

My invention is illustrated by way of example in the accompanying drawings, in which—

Figure 1 shows a front view of the lower 45 part of the casement window and its frame.

Figure 2 shows a sectional plan view of Figure 1.

Figure 3 shows an end view on an enlarged scale of the nut and the screwed rod in position in said nut, and

Figure 4 shows a section on the line A. B. of Figure 3.

Referring now to the drawings; the window 55 1 is hinged to the frame 2 and is held in the desired position by means of the

screwed rod 3 hinged at 4 to the window sash and co-acting with the nut 5 mounted on the window frame 6. As shown in Figures 3 and 4 the said nut 5 is pivotally mounted at 7 in the lugs 8 of the bracket 9 which is 60 screwed to the window frame. The internal thread 10 in the bore of the nut 5 is cut away as shown more particularly in Figures 3 and 4 so that only two or three threads on opposite sides at each end of the nut engage 65 with the screwed rod 3 when the nut is held on the position shown in Figure 4 by means of the leaf spring 11.

It will be readily understood that when it is desired to move the window to a desired 70 position without screwing the rod through the nut the latter can be pressed down against the spring 11 and thus release its threads 10 from the rod and consequently allow the rod to be pushed through the nut. 75 When however, the nut is released, it immediately engages the rod and holds it in the set position.

What I claim is:—

1. Apparatus for opening and closing sky- 80 lights, fanlights, casement windows and the like, comprising a screw threaded rod pivotally mounted on the sash, a bracket mounted on the fixed frame, a mutilated nut pivotally mounted in said bracket adapted to receive said screw threaded rod with a threaded portion on each side of its bore in parallel alignment and a spring bearing against said pivoted nut and tending to keep the internal threads on opposite sides in the bore of said 85 nut in engagement with said screw threaded rod.

2. Apparatus for opening and closing sky- 95 lights, fanlights, casement windows and the like, comprising a screw threaded rod pivotally mounted on the sash, a bracket mounted on the fixed frame, a nut pivotally mounted in said bracket adapted to receive said screw threaded rod, an internal thread in the bore of said nut cut away so that only a 100 small number of threads remain on opposite sides on each end of said nut and a spring bearing against said pivoted nut and tending to keep the internal threads on opposite sides in the bore of said nut in engagement with 105 said screw threaded rod.

In witness whereof I have signed my name to this specification.

WILLIAM SCHONFIELD.
